(57) CLAIM

We claim the ornamental design for a food package, as shown and described.

DESCRIPTION

FIG. 1 is a perspective view of a food container showing our new design, in its display condition in which some portions of the design are not shown for clarity of illustration;

FIG. 2 is a perspective view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a right side elevational view thereof;

FIG. 8 is a left side elevational view thereof; and,

FIG. 9 is an exploded perspective view thereof.

The broken lines, which define the bounds of the claimed design form no part thereof.

The broken lines showing of label in FIG. 1 and other broken lines in the drawings form no part of the claimed design.
